UNITED STATES PATENT OFFICE.

LIZZIE ROYS, OF NEW YORK, N. Y., ASSIGNOR TO THE BUTTERICK PUBLISHING COMPANY, (LIMITED,) OF SAME PLACE.

DESIGN FOR A LADY'S COAT.

SPECIFICATION forming part of Design No. 17,855, dated November 1, 1887.

Application filed September 21, 1887. Serial No. 250,346. Term of patent 3½ years.

To all whom it may concern:

Be it known that I, LIZZIE ROYS, of the city, county, and State of New York, have invented and produced a new and original Design for a 5 Pattern of a Lady's Coat; and I do hereby declare that the engraved prints accompanying this specification convey to any one accustomed to using paper patterns a clear understanding of how a garment made up by the pattern will appear.

The design shows long close-fitting fronts that display a closing down the center to within a short distance of the lower edge, a long close-fitting back having a center seam extending 15 to the lower edge and exhibiting its skirt falling in a group of long forward-turning plaits at either side and in short irregular folds in front of the plaits, coat-sleeves which are partially concealed by wing-sleeves that overlie the sides of the back, curve over the shoulders, 20 and fall in points at their front corners, where they are deepest, and a standing collar.

What I claim as my invention, and desire to secure by Letters Patent, is—

The design for a lady's coat, as shown in the 25 engraved prints accompanying this specification.
